(57) **CLAIM**

I claim the ornamental design for a squirrel baffle, as shown and described.

DESCRIPTION

FIG. 1 is perspective view of a squirrel baffle showing my new design.

FIG. 2 is an enlarged top view of a squirrel baffle shown in FIG. 1.

FIG. 3 is an enlarged bottom view of the squirrel baffle shown in FIG. 1; and,

FIG. 4 is a side elevational view of a squirrel baffle shown in FIG. 1, all the sides being identical.

The broken line showing of environmental structure in FIG. 1 is for illustrative purposes only and forms no part of the claimed design.
